CLAIM

The ornamental design for a pet litter box, as shown and described.

DESCRIPTION

FIG. 1 is a front right top perspective view of a pet litter box.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The broken lines illustrate portions of the pet litter box that form no part of the claimed design.

1 Claim, 7 Drawing Sheets
